UNITED STATES PATENT OFFICE.

HENRY F. STARRETT, OF CHICAGO, ILLINOIS, ASSIGNOR TO STARRETT MFG. CO., OF CHICAGO, ILLINOIS, A CORPORATION OF ILLINOIS.

LOCK.

Application filed January 3, 1921. Serial No. 434,411.

To all whom it may concern:

Be it known that I, HENRY F. STARRETT, a citizen of the United States, residing at Chicago, in the county of Cook and State of Illinois, have invented new and useful Improvements in a Lock, of which the following is a full, clear, concise, and exact description, reference being had to the accompanying drawing, forming a part of this specification.

This invention relates to a lock and more particularly to a combined lock and stop especially adaptable for use with doors provided with cabinets adapted to receive electric panel-boards. These cabinets are usually equipped with a door which permits access to the fuses positioned inside the cabinet, the door being provided with a lock to prevent access to the fuses, except to those authorized to make replacements.

It is the purpose of this invention to produce a combined lock and stop which can be cheaply manufactured, easily installed, and which is simple and efficient in its operation.

One of the objects of the invention resides in the production of an improved form of latch which will cooperate with the locking mechanism, so as to automatically position the latch in the locking position when said latch is rotated in the locking direction until it strikes the enclosure of said locking mechanism.

For the purpose of description, the invention is illustrated in the accompanying drawings in which—

Fig. 1 is a plan view of a portion of the door and cabinet showing the combined locking mechanism and latch in position on the door;

Fig. 2 is a transverse section taken on the plane indicated by the line 2—2 of Fig. 1; and

Fig. 3 is a plan view, similar to Fig. 1, showing the latch in the unlocked position.

As illustrated in the drawing, the locking mechanism 4 is secured to the door 5 in any suitable manner, preferably by rivets such as 6. Any desired form of commercial locking mechanism may be used in which the locking bolt 7 is enclosed in a lock-housing 8. The bolt 7 is controlled by any suitable means enclosed within the housing 8, which, in cooperation with a key, permits the pro-

jection of the bolt 7 from the housing, as shown in Fig. 1, or the withdrawal of the bolt 7 from the locking position, as shown in Fig. 1, to a position in the housing, as shown in Fig. 3. The locking mechanism enclosed within the housing is positioned on the door so that the medial line of the lock will pass substantially through the center of rotation of the latch 10.

The latch comprises the locking member 11 and the two rearwardly projecting prongs 12 and 13, the prongs 12 and 13 and the locking member 11 being slightly elevated above the horizontal plane of the remainder of the latch member 10, as clearly illustrated in Fig. 2. Due to this elevation of the locking member 11 when the latch is turned to the locking position, as illustrated in Figs. 1 and 2, the locking member will ride in back of the strike-plate 14 secured to the cabinet enclosure 15, which strike-plate functions to properly position the door 5 so that its front surface will rest flush with the front surface of the top of the cabinet enclosure 15. The rearwardly projecting prong 12 serves as a stop to automatically limit the turning of the latch in its locking position when the latch is turned from the unlocked to the locked position. When the latch is thus turned, due to the relative positions in which the locking mechanism 4 and the latch 10 are placed on the door, the prong 12 will hit the housing of the locking member 4, so as to arrest the turning movement of the latch. When the locking member of the latch is in the locking position, as shown in Figs. 1 and 2, the prongs 12 and 13 are so positioned with respect to the locking bolt 7 of the locking mechanism 4, that this bolt will ride between the two prongs when the bolt is projected to its locking position.

The latch 10 is secured to the door 5 in any suitable manner, preferably by means of a screw such as 16 which extends through a perforation in the latch into a screw-threaded handle 17 on the front side of the door by means of which the latch is controlled. The screw 16 also extends through a spring washer 18 which serves to rigidly hold the washer against the head of the screw 16 and whereby the latch 10 will rotate with the handle 17.

It will now be evident from the foregoing description that due to the relative location

2 of the latch 10 and the locking mechanism 4 and the construction of the latch 10, including the prongs 12 and 13, that the rotation of the latch to the locking position will be automatically arrested by the prong 12, and that when the latch is thus arrested in its rotary movement the prongs 12 and 13 will be automatically positioned so that they will cooperate with the locking bolt 7 to lock the latch in its locking position.

The housing of the locking mechanism 4, due to its location with respect to the rotatable latch 10, therefore, serves the dual function of a stop for arresting the movement of the latch in its locking position and for locking the latch in this position after it has been thus located. The locking mechanism and latch, when positioned as hereinbefore described with the latch equipped with the combination lock and stopping prong, consequently provide a simple and efficient means for securing a latch locking combination.

Obviously, the invention is not limited to the specific embodiment thereof herein illustrated and described, but is capable of other variations and applications within the spirit and scope of the invention as set forth in the following claims.

39 What I claim as new and desire to secure as Letters Patent is:

1. In a device of the character described, in combination, a locking mechanism com-

prising a reciprocating locking bolt, a rotatable latch comprising a locking member, projecting prongs positioned on said latch, one of said prongs cooperating with said locking mechanism to position the said latch in the locking position, and both of said prongs cooperating with said locking bolt to lock said latch.

2. In a device of the character described, in combination, a locking mechanism positioned in a housing secured to a door, a rotatable latch secured to said door, lock position and receiving means integrally secured to said latch, said latch and locking mechanism being so positioned relative to one another to cause said latch to be automatically positioned in the locking position by the cooperative action of said means and said locking mechanism.

3. In a device of the character described, in combination, a locking mechanism positioned in a housing secured to a door, a rotatable latch secured to said door, projecting prongs integral with said latch, said latch and locking mechanism being so positioned relative to one another to cause said latch to be automatically positioned in the locking position by the cooperative action of one of said projecting prongs and said locking mechanism.

In witness whereof, I have hereunto subscribed my name.

HENRY F. STARRETT.
